Primary Examiner — Darlington Ly(74) *Attorney, Agent, or Firm* — Birch, Stewart, Kolasch & Birch, LLP(57) **CLAIM**

The ornamental design for a motorcycle, as shown and described.

DESCRIPTION

FIG. 1 is a front and right side perspective view of a motorcycle embodying our new design;

FIG. 2 is a rear and left side perspective view thereof;

FIG. 3 is a front and left side perspective view thereof;

FIG. 4 is a rear and right side perspective view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a top plan view thereof; and,

FIG. 10 is a bottom plan view thereof.

The broken lines in the drawings illustrate portions of the motorcycle that form no part of the claimed design.
